UNITED STATES PATENT OFFICE.

JOSEPH R. MUELLER, OF MADISON, MINNESOTA.

WHEEL-PLOW.

No. 906,051.

Specification of Letters Patent.

Patented Dec. 8, 1908.

Application filed February 4, 1908. Serial No. 414,231.

To all whom it may concern:

Be it known that I, JOSEPH R. MUELLER, citizen of the United States, residing at Madison, in the county of Lac qui Parle and State 5 of Minnesota, have invented certain new and useful Improvements in Wheel - Plows, of which the following is a specification.

The present invention relates to certain new and useful improvements in plows, and 10 more particularly to a novel attachment for the same whereby the plow may be prevented from running sidewise when employed upon the side of a hill.

The object of the invention is to design an 15 attachment of this character which can be readily applied to the plow rod for the purpose of rendering the same longitudinally adjustable, and which will cause the plow to cut the same width upon one side of the hill 20 as upon the opposite side.

For a full description of the invention and the merits thereof and also to acquire a 25 knowledge of the details of construction and the means for effecting the result, reference is to be had to the following description and accompanying drawings, in which:

Figure 1 is a perspective view of a wheel plow having the invention applied thereto. Fig. 2 is an enlarged perspective view showing 30 the parts of the invention detached from the plow. Fig. 3 is a top plan view of the rear clamp. Fig. 4 is an enlarged detail view of the connection between the link and the rear clamp member. Fig. 5 is a sectional view through the forward clamp member, portions being broken away.

Corresponding and like parts are referred to in the following description and indicated in all the views of the drawings by the same 40 reference characters.

In general the invention is in the nature of an attachment for a plow, the said attachment being designed to render the plow rod longitudinally adjustable whereby the rear 45 furrow wheel can be turned to throw the plow either to the right or to the left.

Referring to the drawing the numeral 1 designates the plow rod which extends from the front furrow wheel 2 to the rear furrow 50 wheel 3 and is made extensible by means of the attachment. The usual plows 4 are shown and a tongue 5 of the conventional construction is utilized for applying draft to the implement.

55 The plow rod 1 is severed at a point toward the forward end thereof and comprises a

front section 1^a and a rear section 1^b. Applied to the plow rod at the junction of the two sections is a clamp comprising an upper member 6^a and a lower member 6^b, opposite ends of the two clamping members being connected by U bolts 7 and the lower clamping member 6^b being provided with a set screw 8 for engaging the front section 1^a of the plow rod, while the upper clamping member 6^a is provided with a segmental rack 9. Owing to the action of the set screw 8 the front section 1^a of the plow rod is rigidly engaged by the clamp while the rear section of the plow rod is adapted to 70 slide freely within the same. A second clamp is applied to the rear section 1^b of the plow rod and comprises the companion clamping members 10^a and 10^b which fit against opposite sides of the plow rod and 75 are turned at an angle of approximately ninety degrees to the corresponding clamping members 6^a and 6^b. U bolts 11 serve to connect the members 10^a and 10^b of the rear clamp and the member 10^a is provided with 80 a set screw 12 designed to engage the rear section of the plow rod to produce a rigid connection therewith. Projecting laterally from the member 10^b of the rear clamp is a pivot stud 13 engaging the rear end of a link 85 14, the forward extremity of the link being engaged by a lateral pin projecting from the end of a crank 15. Specifically describing the connection between the link and the rear clamp member, it will be observed that the 90 rear end of the link is provided with a key hole slot 19 and that the pivot stud 13 is formed at its extremity with a rearwardly extending arm 20. With this construction 95 link 14 is swung rearwardly the key hole slot 19 will register with the arm 20 and the link can be detached from the pivot stud or placed thereon as may be desired, while when the link is swung forwardly the arm 20 will 100 prevent accidental displacement thereof. The pivot end of this crank is formed with an arm 16 extending through the base of the segmental rack 9 and having the operating lever 17 applied to the extremity thereof, the 105 said operating lever carrying a dog 18 for engagement with the notches of the said rack. It will thus be apparent that by moving the operating lever the crank 15 will act through the medium of the link 14 to bring 110 about a longitudinal movement of the rear section of the plow rod. In this manner the

plow rod can be adjusted and the rear furrow wheel 2 turned either to the right or to the left as may be required to prevent the plow having a sidewise movement.

5 Having thus described the invention, what is claimed as new is:

10 1. The combination of a plow provided with a sectional plow rod, a member having a rigid connection with one of the sections of the plow rod and a sliding connection with the opposite section, a second member rigid with the second mentioned section of the plow rod, an operating lever mounted upon the first mentioned member, a pivot stud 15 projecting from the second mentioned member and formed with a lateral arm, and a link having an operative connection with the lever and provided with a key-hole slot for receiving the pivot stud and the arm projecting therefrom.

20 2. The combination of a plow provided with a sectional plow rod, a member having a rigid connection with one of the sections of the plow rod and a sliding connection with the opposite section, a rack upon the said member, a crank pivoted upon the rack, a lever rigid with the crank and provided with 25 means for engaging the teeth of the rack, a second member rigid with the second mentioned section of the plow rod, a pivot stud

projecting from the said second member and provided with a laterally extending arm, and a link connected to the crank and formed with a key-hole slot for receiving the stud and the arm projecting therefrom.

3. The combination of a plow provided with a sectional plow rod, a clamp comprising companion clamping members applied to opposite sides of the plow rod and having a rigid connection with one of the sections of the plow rod and a sliding connection with the opposite section, an operating lever mounted upon the said clamp, a second clamp also comprising companion clamping members applied to opposite sides of the second mentioned section of the plow rod and rigid therewith, the companion members of the second clamp being disposed at angles to the corresponding companion members of the first mentioned clamp, a pivot stud projecting from the second clamp, and a link loosely mounted upon the pivot stud and having an operative connection with the operating lever.

55 In testimony whereof I affix my signature in presence of two witnesses.
